CALENDAR PENCIL

Sylvester G. Lipic, St. Louis, Mo.

Application April 4, 1941, Serial No. 386,796

4 Claims. (Cl. 40—108)

The present invention relates generally to improvements in calendar pencils and more particularly to novel perpetual calendar mechanism which may be incorporated in a pencil, fountain pen or the like.

Primarily an object of the invention is the incorporation of the perpetual calendar mechanism in the upper end of a pencil or similar device, thus entailing no changes whatever in the conventional structure therebelow.

Another object is the inclusion in said mechanism of means whereby accidental displacement of the parts relative to one another is obviated when the pencil, or similar article, is in ordinary use.

A feature of the invention resides in the few parts required, and the simple and easy manner in which manipulation thereof provides a perpetual calendar for ready reference.

Other objects and features will be apparent or pointed out in the following description and in the accompanying drawing, wherein similar reference characters designate similar elements throughout the various views.

In the drawing:

Fig. 1 is a front elevational view of a pencil embodying my invention;

Fig. 2 is a side elevational view thereof, the lower portion of the pencil being broken away;

Fig. 3 is a rear elevational view thereof, the lower portion of the pencil being broken away and a cap portion being in raised position;

Fig. 4 is a vertical sectional view on the line 4—4, Fig. 2, on a greatly enlarged scale;

Fig. 5 is a similar view, the parts occupying a position corresponding to Fig. 3;

Fig. 6 is a horizontal section on the line 6—6, Fig. 2, on an enlarged scale;

Fig. 7 is a similar view illustrating another position which certain parts may occupy;

Fig. 8 is an enlarged plan view of a cylindrical member provided with seven equally spaced slots or cut-out portions; and

Fig. 9 is a view on an enlarged scale of the several components in aligned but separated position.

With particular reference to Fig. 1, the drawing illustrates a pencil of conventional design including a barrel A, a clip B, an eraser and spare lead container portion C, a tip D, and a point E. The mechanism of my invention is mounted on and supported by the upper end of said barrel.

The visible components of the calendar comprise a cylindrical shell member 10, and a com-

plementary cap member 11, the former having imprinted or engraved thereon seven vertical columns of numerals indicating the days of a month, and the latter a horizontal row of alphabetical characters indicating the seven days of a week.

5 A cylindrical plug 12, press fitted or adhesively secured within the lower end portion of the bore of the member 10 and the upper end portion of the bore of the barrel A serves to secure the former permanently in place on the latter. A metal ring 13 may be interposed between the upper edge of the barrel and the lower edge of the cylinder, for ornamental reasons, but is not essential.

10 15 Press fitted into, or otherwise permanently secured within the bore of the member 10 at its upper end, is the major portion of a cylindrical bushing 14, provided with a rounded lower margin 15 facilitating its insertion. Said bushing is provided with seven recesses or notches 16, one for each day of a week. As shown in the drawing, the recessed or notched portion of the bushing 14 extends above the members 10 and into the bore of the cap 11 wherein it has a 20 sliding fit.

25 Permanently imbedded in said cap 11 is a plug 17, longitudinally bored as at 18 and transversely as at 19. The numeral 20 indicates a vertical pin press fitted into the bore 18, and the numeral 21 indicates a horizontally disposed pin inserted in the bore 19. The diameter of the pin 21 is slightly smaller than the width of any of the notches 16, to facilitate its entrance into and withdrawal from each of said notches.

30 35 Interposed between the head portion 22 of the pin 20 and a washer 23, which surrounds said pin and abuts the lower extremity 15 of the lock bushing 14, is a coil spring 24 which as illustrated also surrounds said pin. As shown particularly in Figs. 4 and 5, the reduced portion 25 of the plug 17 has a sliding fit within the bushing 14.

40 45 In order to set the calendar for any month it is merely necessary to grasp the cap portion 11, draw it away from the fixed cylindrical member 10, and turn it to the right or left until the proper day of the week coincides with the proper date of the month. At that time the pin 21 is suspended directly above one of the notches 16 of the lock bushing. Fig. 5 clearly indicates this. Release of the cap portion 11 automatically causes the pin to enter the recess 16 therebelow, due to the expansion of the spring 24.

50 55 With the pin 21 in a recess 16 of the bushing 14 and the cap 11 firmly held pressed against the upper edge of the date indicating shell 10, Fig.

4, accidental changing of the setting is practically impossible. The setting operation is simplified due to the round configuration of the pin 21 and the fact that the width of each recess 16 is greater than the diameter of said pin.

In Figs. 1, 2, 4 and 6, it is assumed that the first day of a month is a Sunday, and that the pin 21 is in alignment with the letter S on the cap 11. In Figs. 3 and 5 the cap 11 is shown in elevated position ready to be turned to the right or left to obtain a new setting. In Fig. 7, assuming the pencil to be in the same relative position as in Fig. 6, it is seen that the pin 21 is located in the second recess 16 to the left of that in which it is found in Fig. 6, indicating that the first day of the month in that setting is a Tuesday.

From the foregoing description it is apparent that a novel, simple and easily manipulated perpetual calendar pencil mechanism is provided, which may be readily applied to conventional pencils, fountain pens and similar devices. While a preferred form has been illustrated and described, obviously the invention may be modified in some respects without departing from the spirit thereof. Therefore I do not wish to be limited to the precise details of construction illustrated.

I claim:

1. In a calendar pencil including a barrel, a cylindrical shell mounted on and supported by the upper end of said barrel, seven vertical rows of numerals indicating the days of a month imprinted on said shell, a co-axially aligned cap having axial and rotative movements positioned above the shell with its lower edge contacting the upper edge of the shell, a horizontal row of seven evenly spaced alphabetical characters indicating the days of the week imprinted on the cap, a bushing provided with seven evenly spaced notches fixed in the shell, a horizontal pin fixed in the cap and extending into one of the notches in said bushing, a vertical pin fixed in said cap, an integral head formed on the lower end of said pin, and a spring interposed between the head of the vertical pin and the bushing whereby said cap may be manually elevated and rotated about its axis until said horizontal pin is in position above any one of said notches and upon release of the cap said horizontal pin is forced into and maintained in the notch selected.

2. In a calendar pencil including a barrel, a cylindrical shell mounted on and supported by the upper end of said barrel, seven vertical rows of numerals indicating the days of a month imprinted on said shell, a co-axially aligned cap having axial and rotative movements positioned above the shell with its lower edge contacting the upper edge of the shell, a horizontal row of seven evenly spaced alphabetical characters indicating the days of the week imprinted on the cap, a bushing provided with seven evenly spaced notches fixed in the shell and extending there-

above and into said cap, a plug secured in the cap, a horizontal pin carried by said plug engaging a selected notch of said bushing, a vertical pin having an enlarged head portion secured in said plug, a washer surrounding the pin and abutting the lower edge of said bushing, and a coil spring about said pin interposed between the head portion thereof and the underside of the washer whereby said cap may be manually elevated and rotated about its axis until said horizontal pin is in position above any one of said notches and upon release of the cap said horizontal pin is forced into and maintained in the notch selected.

3. In a pencil or similar device having a barrel portion, a perpetual calendar assembly attached to and supported on the upper end portion of the barrel, the assembly including a stationary, cylindrical shell on whose outer periphery are imprinted seven vertical rows of numerals corresponding to the days of a month, a manually axially and rotatively adjustable cap member on whose outer periphery is imprinted a horizontal row of alphabetical characters corresponding to the initials of the days of a week, a bushing provided with seven equally spaced recesses fixed in said shell, a horizontal cylindrical member carried by the cap member and adapted to register with a selected notch in said bushing, a vertical headed pin fixed in said cap member extending into the bore of the shell, and a coil spring about said pin interposed between the head thereof and the bushing adapted to permit manual elevation and rotation of said cap member and said vertical pin to a desired location, and then to cause the horizontal cylindrical member of the cap to automatically enter the selected notch upon manual release of the cap.

4. Calendar mechanism mounted on and supported by the upper end barrel member of a pencil or similar article, comprising a stationary cylindrical shell having seven vertical rows of numerals indicating the days of a month imprinted on its outer periphery, a vertically reciprocable and horizontally rotatable cap having a horizontal row of seven alphabetical characters indicating the days of a week imprinted thereon positioned above said shell, a plug secured within said cap and having a reduced depending portion extending below the lower edge of the cap, a vertical pin secured within the plug and provided with an enlarged head, a stationary bushing fixed in said shell, a washer surrounding said vertical pin and abutting the lower end of the bushing, a coil spring around said pin interposed between said head and washer, seven equally spaced notches provided along the upper margin of said bushing and extending above the upper edge of the shell, and a horizontal pin carried by said plug adapted to enter and be withdrawn from any one of said notches.

SYLVESTER G. LIPIC.
